(Cl. D58—12)

To all whom it may concern:

Be it known that we, William C. P. Zabel and Paul Young, citizens of the United States of America and residents of Chicago, in the county of Cook, and State of Illinois, and Midland, in the county of Midland, and State of Michigan, respectively, have invented a new, original, and ornamental Design for a Box Cover, of which the following is a specification, reference being had to the accompanying drawing, forming part thereof:

Figure 1 is a top plan view of a box cover showing our new design.

Fig. 2 is a bottom plan thereof of Fig. 1.

Fig. 3 is an edge view taken from the right-hand edge thereof shown in Fig. 2.

Fig. 4 is an edge view thereof taken from the bottom edge of the device of Fig. 2.

Fig. 5 is an enlarged fragmentary cross-sectional view thereof, taken on the line 5—5 of Fig. 1.

We claim:

The ornamental design for a box cover, as shown.

WILLIAM C. P. ZABEL.
PAUL YOUNG.
